(57) **CLAIM**

The ornamental design for a tablet computer as shown and described.

DESCRIPTION

1. Tablet computer
- 1.1 : Front
- 1.2 : Back
- 1.3 : Left
- 1.4 : Right
- 1.5 : Top
- 1.6 : Bottom
- 1.7 : Perspective
- 1.8 : Perspective

The design product is used for data processing, recording, voice transcription, handwriting recording, etc; the characteristic features of the design lie in the shape of the tablet computer; the best view showing the main points of this design is the reproduction 1.7.

1 Claim, 8 Drawing Sheets
